UNITED STATES PATENT OFFICE.

CHARLES M. HORTON, OF PORTSMOUTH, NEW HAMPSHIRE, ASSIGNOR TO
THE SINGER MANUFACTURING COMPANY, A CORPORATION OF NEW
JERSEY.

MACHINE FOR FORMING KNOTTED-THREAD FASTENINGS.

No. 857,941.

Specification of Letters Patent.

Patented June 25, 1907.

Application filed October 3, 1904. Serial No. 226,954.

To all whom it may concern:

Be it known that I, CHARLES M. HORTON, of Portsmouth, in the county of Rockingham and State of New Hampshire, have invented certain new and useful Improvements in Machines for Forming Knotted-Thread Fastenings, of which the following is a specification.

This invention relates to machines which secure together separate articles by means of knotted thread fastenings which consist of loops of thread or string passed through or around portions of the article, the ends of which are tied together to securely hold the same, and consists essentially of a machine having means such as a needle for carrying a thread or string through and around portions of the articles to be connected, knot-tying fingers adapted to grip the loose end of the thread or string and carry it through a bight or loop in the thread pulling it tight to form a knot, and a cutter for severing the thread after the knot has been tied.

In this application the devices which constitute my invention are shown and described as being applied to a machine for sewing buttons to cards, but it is to be understood that they can as well be used with any other machine which performs a similar class of work, for instance, to a machine adapted to pass a string through opposite eyelet-holes of an unlasted shoe upper and tie the ends of the string together to form a single fastening for holding the fly of the upper closed during the process of lasting, that here employed having been chosen simply for convenience of illustration, as with such a machine the construction and operation of my knot-forming and tying devices can most easily be demonstrated.

Of the accompanying drawings,—Figure 1 represents a side elevation, Fig. 2 represents a front elevation, Fig. 3 represents a section on line 3—3 of Fig. 1, Fig. 4 represents a plan view, and Fig. 5 represents an elevation of the opposite side from that seen in Fig. 1, of a machine for sewing and tying buttons to cards, provided with instrumentalities embodying my invention. Fig. 6 represents a sectional front elevation of a portion of the head of the machine, showing on an enlarged scale the presser, cutter-operating mechanism and needle. Figs. 7 and 8 represent op-

posite side elevations of the same. Fig. 9 represents a view similar to Fig. 7 but showing the parts in a different position. Fig. 10 represents a perspective view showing the presser foot and thread-cutter. Fig. 11 represents a sectional plan view taken on line 11—11 of Fig. 7. Fig. 12 represents a sectional view on line 12—12 of Fig. 6. Fig. 13 represents a vertical section of the knife-block. Figs. 14 and 15 represent perspective views of the thread-cutting knife and bottom plate of the presser-foot respectively. Fig. 16 represents a plan view, Fig. 17 represents a vertical section, and Fig. 18 represents a horizontal section on line 18—18 of Fig. 1, of the gripping members which constitute the looping and tying devices and actuating mechanism therefor. Fig. 19 represents a rear elevation of the two gripping members. Fig. 20 represents a vertical sectional view of one of said members, and Fig. 21 represents a similar view of the other member. Fig. 22 represents in perspective the detailed parts of the gripping member shown in Fig. 21, and Fig. 23 is a similar view illustrating the member shown in Fig. 20. Fig. 24 represents a front elevation of the cam which laterally operates said gripping members. Fig. 25 represents a similar view showing the gripping member actuating bars in position relatively to the cam. Fig. 26 represents a perspective detail view of the member by which the fingers of the gripping members are separated. Figs. 27 to 43 inclusive represent views showing the various positions occupied by the knot-tying devices during the operation of forming a knot, and the various stages of the knot, Fig. 43 showing the knot completed and the button secured to the card.

The same reference characters indicate the same parts in all the figures.

The machine illustrated in the drawings comprises a frame 1 having a head portion 2 in which the needle-operating mechanism is contained. The needle 3 is carried by a needle-bar 4 which is caused to reciprocate vertically in guide-ways carried by an oscillatory frame 5 journaled on bearing-screws 6. The needle-bar and needle are reciprocated vertically from the main drive-shaft 7 through the bevel gears 8 9, shaft 10, bevel gears 11 12, and horizontal shaft 13 which

carries a crank member 14 connected by link 15 with the needle-bar in the manner usual with machines for sewing buttons. The frame 5 which carries the guides for the needle-bar is oscillated to move the needle laterally by means of an arm 16 rigid with the frame and a link 17 pivoted at one end to the bar 16 and adjustably connected at its other end with a link or arm 18 pivoted at 19 to the frame and having a stud 20 which engages the groove 21 of a cam 22 which is mounted to rotate on the frame of the machine and provided with a bevel gear portion 23 in mesh with a bevel gear 24 carried by the shaft 13 through which it receives its motion. As the connection between the link 17 and arm 18 is shifted toward or away from the pivot 19 the lateral throw of the oscillating frame 5 is diminished or increased, whereby the lateral feed of the needle may be adjusted to suit work of varied character.

While the present improvement is herein represented as embodied in that class of sewing machines having a reciprocating needle-bar mounted in a laterally moving frame, it is evident that the relative lateral movement between the needle and the work may be produced by any suitable or well-known means to enable the needle to pass loops of needle-thread first through one point and then through another point in the work spaced therefrom in order that the thread may embrace a portion of the material to be inclosed by the knotted stitch.

The shaft 13 is designed to rotate at a uniform speed, thereby reciprocating the needle regularly while the relation between the gears 23 and 24 and the shape of the cam-groove 21 is such that the needle is held in one position, that is the first position in the cycle of operations by which a complete fastening is formed, while it is caused to make one reciprocation and is then shifted laterally to its second position and there held while two additional reciprocations are made. During these two reciprocations in the second position the knot-forming devices hereinafter described are operated to form two knots or half hitches in the thread to secure the ends of the fastening together, after which the thread is cut off and the needle returned to its first position to repeat the operations on a new piece of work.

The machine is provided with a presser-bar 25 which carries a presser-foot 26 and is reciprocated vertically in the manner usual in machines of this character to alternately bear upon and release the work supported on the table 27. The presser-foot carries a knife 28 which is operated by mechanism which will now be described to cut off the thread at the conclusion of each cycle of knot-tying operations, the said mechanism being shown in Figs. 1 and 5, and details thereof in Figs. 6 to 65 15 inclusive.

The bottom of the presser-foot 26 is provided with a horizontal plate 27 which is adapted to bear upon the work and is formed with a slot 28 through which the needle carrying the thread is adapted to pass, one of the edges of which is sharpened and is adapted to coact with the knife 29 to shear off the thread at the proper time. On the presser-foot is formed a guide 30 in which is mounted a knife-block 31 to which the knife 29 is connected. The block and knife are reciprocated by means of a lever 32 having a stud 33 which engages a slot in the knife-block and causes the latter to move in the guide 30 when the lever 32 is oscillated. The said lever is pivoted at 33 to a block 34 which is connected to and carried by the presser-bar 25 and is provided with a cam-slot 35. A bell-crank-lever 36 is also carried by the bar 25 by means of a pivotal connection 37 to a block 38 mounted on the bar. The bell-crank has a stud 39 which projects into the cam-slot 35 and has a pivotal connection at 40 with a link 41 which is pivoted to the bell-crank lever 42 mounted on a pivotal bearing 43 in the machine-frame. The lever 42 has on one of its arms a stud 44 which is engaged with a groove 45 in the cam-disk 46, which disk is rotatably mounted on the machine-frame and rotated by the bevel gear 24 meshing with a gear 47 connected to the cam-disk.

The upper portion of the cam-slot 35 is curved concentrically with the pivot 37 so that when the bell-crank 36 is operated to move the stud 39 from the position shown in Fig. 9, upwardly the lever 32 is not operated thereby, but the lower portion of the slot 35 is eccentric to the pivot and thereby the motion of the stud 39 from the position shown in Fig. 9 to that of Figs. 5 and 7 operates lever 32 to advance the knife across the slot 28 and shear off the thread. The circular upper portion of the slot 35 permits the bell-crank 36 to have considerable latitude of movement for a purpose hereinafter described, without actuating the lever 32.

The upper end of the vertical arm of bell-crank 36 is provided with a thread-guide 48 which is located between and in proximity to a guide 49 on a lever 50 and a guide 51 fixed on the head of the machine. The course of the thread is from the spool 52, through a guide 53, about a tension device 54, through an eye in the take-up lever 55, thence through the guides 49 48 51, a second fixed guide 56, and a thread-clamp to the eye of the needle 3. The tension device and take-up are of the usual form and need not be particularly described here, as they do not form any part of my present invention.

The function of the guide 48 carried by the bell-crank 36 is to measure off enough thread at the conclusion of each cycle of fastener-forming operations to provide a sufficient supply to begin the next knot-forming opera-

tion. For this purpose the guide 48 is moved away from the guides 49 and 51 during the upward movement of the needle in the final operation to draw a certain amount of thread past the tension device. This motion is produced by the offset part 57 of the cam-groove 45 which causes the upper arm of the bell-crank 42 to be moved downward and the lower arm to be moved forward; thus advancing the part 48 of the bell-crank 36 and causing the stud 39 to rise in the concentric portion of the cam-slot 35. Immediately thereafter the bell-crank 36 is returned by the projection 58 of the cam which is designed to move the lever 36 to its extreme backward position and force the stud 39 into the eccentric part of the slot 35 to cause the cutter to sever the thread, and immediately thereafter the cam 46 advances the bell-crank slightly to cause the retraction of the knife. These operations take place at the conclusion of the last stroke of the needle in the cycle of operations and before the needle has begun to descend to form a new fastening.

As the knife is carried by the presser-foot and occupies the same relation to the needle that the presser-foot does, it is evident that its distance from the upward limit of the motion of the needle will vary according to the thickness of the work acted upon and that therefore the length of the thread cut off will vary similarly. In order to insure that the amount of slack thread furnished to the needle at the beginning of each series of operations is the same, regardless of the thickness of the work operated on, the lever 50 before referred to is provided for coacting with the bell-crank 36 in measuring off the supply of thread. This lever 50 is pivoted at 59 to the machine-head and is provided with an arm 60 having a beveled portion adapted to be engaged by the block 38 when the presser-bar is raised. Thus when material of considerable thickness is beneath the presser-foot, the block 38 is engaged with the arm 60 and the thread-guide 49 carried by the lever 50 is moved rearwardly, and conversely, when work of less thickness is acted on the guide 49 is moved forward; thus the distance which the guide 48 is caused to move from the guide 49 during the thread-measuring operation of the bell-crank 36 is caused to vary according to the thickness of the work and more thread is drawn from the tension device when the presser-foot is elevated than when it is depressed.

At the last reciprocation of the needle after one knot has been tied and the needle has begun to descend on its final reciprocation to tie the second knot, there is liability of the thread becoming looped loosely around the needle, which will prevent the formation of the knot, for it is necessary that the thread should draw in the right direction from the

needle in order that the knot may be properly formed. To prevent this fouling of the needle I provide a clamp which holds the thread taut during the beginning of the final descent of the needle and until it enters the work. This clamp consists of a stationary member 62 mounted on the head of the machine and a movable member 63 which is adapted to coöperate with the fixed member to clamp the thread, between which member the thread is guided. The movable member comprises a rod 64 having its forward end bent to form the clamp member 63 and is acted upon by a spring 65 which bears against a collar on the rod and an abutment 80 on the machine-head to cause the movable clamp to engage the fixed clamp. The rod 64 is connected to one arm of a lever 66 pivoted to the frame, the other arm of which rests against the surface of the cam 22 and is held in contact therewith by the pressure of the spring 65. The cam normally holds the lever 66 in such a position that the clamp members are retained out of engagement and is provided with depressions 67 and 68 which are so located as to permit the clamp 63 to be moved by the spring to engage the thread at the proper times. One of these depressions comes into engagement with the lever 66 at the beginning of the last descent of the needle and allows the clamp to grip the thread and hold it until the needle enters the work, after which the thread is released and is allowed to be drawn out by the needle, and the other depression operates the lever to cause the thread to be clamped at the end of the knot-forming series of operations after the bell-crank 36 has measured off the supply of thread and while the knife is cutting the thread, in order to hold the thread taut and insure the severing thereof.

Below the work-table 27 are mounted knot-tying devices which engage the thread fed through the work by the needle and are manipulated to form knots. These devices comprise a pair of gripping members 71, 72 which are pivoted in a holder 73. The gripping member 71 has pivoted to it a nipper 74 and the member 72 carries a pivoted nipper 75. The gripping portions of the members 71 and 74 are slotted to form a plurality of fingers or jaws which hold the thread so that it extends across the slot and the gripping parts of the member 72 and nipper 75 are shaped so that they can enter the said slot and engage the thread carried by the member 71 and extending across the slot. The gripping members 71 and 72 are mounted coaxially in any desired manner, the construction here illustrated consisting of a sleeve 125 carried by the member 72 and journaled in the holder 73, and a pin 76 formed on the member 71 and journaled in the interior of the sleeve, these parts being held in position by a stud 77 screwed into the 13c

pin 76 and extending over the end of the bearing in the holder. Arms 78 79 are similarly mounted in a fixed bearing 80 formed in a portion of the frame of the machine and these arms are provided with lugs or tenons 81 82 which engage the gripping members 71 72 respectively. The arms are also provided with studs 83 84 which are engaged in cam-grooves 85 86 of a cam-disk 87 and are thereby actuated to move the grippers toward and from each other at the proper times.

The holder 73 is journaled in a bearing 88 in the machine-frame so as to be capable of turning about an axis which is substantially perpendicular to the axis about which the gripping members are moved, whereby the latter are adapted to be moved in all directions. The cam-groove 89 formed in a cam 90 on the shaft 7 operates a stud 91 carried by a rock-arm 92 and connected to a rock-arm 93 mounted on the holder 73 through a link 94 to oscillate the holder and the gripping members about the axis 88. The nippers 74 and 75 are operated alternately to cause first one and then the other to grip and release the thread by means of a rod 95 which is mounted for reciprocating motion in a guide-way formed in the center of the bearing 80 and is operated by a cam-groove 96 on the cam 90. The rod 95 carries projections 97 which engage projecting arms formed on the nippers 74 and 75 on opposite sides thereof, whereby when the rod is moved toward the right, reference being had to Figs. 17 and 18, the nipper 74 is caused to open and when moved to the left the nipper 75 is opened.

The operation of the knot-tying devices will now be described, reference being had to Figs. 27 to 43 inclusive: At the beginning of each series of operations by which a fastening is formed, the needle and gripping members occupy the position shown in Figs. 27, 28 and 29. As the needle advances and projects through the work, the gripping member 71 is advanced into the path thereof and the nipper 74 is opened so that the main portion of the gripping member and the nipper are on opposite sides of the needle. As the needle is retracted the nipper is operated to grip the end of the thread left by the needle below the work in the manner shown in Fig. 33, the nipping of the needle-thread being delayed until the needle has risen entirely above the work and the initial loop of thread has been drawn up through the fingers or jaws of the nipping and loop-taking member 71 74 sufficiently to leave only a short end of thread beneath the work suitable for passing through the subsequently formed needle loops of the same stitch-forming cycle. The needle is then shifted laterally by the mechanism previously described and is again advanced through the work in its second position, the gripping member having been

shifted to one side of the needle as shown in Fig. 34. As the needle starts to rise again it forms a loop of thread beside the gripper and the latter is then operated by the cams described, to move first to the left, then toward the rear and toward the right again to advance the end of the thread held by it around the needle and through the loop, this operation being shown in Fig. 35. At this point the second gripping member 72 is caused to advance and its thread-engaging portions are moved into the slots of the corresponding parts of the member 72 and are then operated to grip the thread, the member 72 being caused at the same time to release the thread. The member 72 then backs off as the needle rises and pulls the thread taut to form a knot as shown in Fig. 37, the knot being more clearly shown on an enlarged scale in Fig. 38. These operations form one half-hitch and it is necessary to form another hitch in order to retain the fastening. For this purpose the gripping member 71 is again advanced and caused to take the end held by the member 72 from the latter. The needle is then caused to descend again in the same place and the identical operations above described are repeated, forming the knot shown in Figs. 42 and 43.

As above described, the lower thread-handling devices comprise a thread-nipping and loop-taking member 71 74 which alone cooperates directly with the needle in receiving the thread-loops passed through the work by the latter, and a thread-nipping holding device consisting of the member 72 75 which cooperates merely with the loop-taking member in holding the thread-end while such member recedes from the thread-loops through which it passes the thread-end. It will also be seen that as above described the thread-end is passed successively through different thread-loops in the same direction to produce a particular form of knot. It is obvious, however, that the character of the several actuating cams will determine the direction and timing of the operative movements of each of these thread-nipping members and the character of their cooperation with the needle and the consequent nature of the knot produced. Thus, were the thread-end to be passed through the loops presented by the needle alternately by the different thread-nipping members, a knot of different character than that produced by the mode of operation hereinbefore described, as represented in Fig. 43, would be produced.

According to the present improvement, in its preferred form, the thread-nipping members receive their operative or thread-engaging movements in parallel planes, while they receive lateral positioning movements corresponding with those of the needle in directions transversely of such operative movements; thus insuring the comparative sim-

plicity of the mechanism in construction and arrangement and certainty of coöperation of the members between which the thread is successively passed in the cycle of operation 5 of the machine.

It is evident that these knot-tying devices are not restricted for use with a sewing-machine and that other instrumentalities than a needle might be used for advancing the 10 thread through the work, as any device having means to guide a thread or string and having sufficient rigidity to carry the same forward might be employed. I therefore do not wish to limit my claims to mechanism in 15 which a needle is employed, but desire to include any structure provided with a suitable thread-carrier having the necessary qualities referred to.

I claim:

20 1. In a machine for making knotted thread-fastenings, in combination, a reciprocating thread-carrier adapted to pass thread-loops through the work, actuating means for imparting to said thread-carrier in each knot-forming cycle an initial reciprocation and a plurality of subsequent reciprocations, means for producing a relative lateral movement between the thread-carrier and the work, means for actuating the same once 25 only for each knot-forming cycle, and means for passing the end of an initial thread-loop through each of the subsequent thread-loops of a cycle.

2. In a machine for making knotted thread- 30 fastenings, in combination, a reciprocating thread-carrier adapted to pass thread-loops through the work, actuating means for imparting to said thread-carrier in each knot-forming cycle an initial reciprocation and a plurality of subsequent reciprocations, means for producing a relative lateral movement 35 between the thread-carrier and the work, means for actuating the same once only for each knot-forming cycle, and means for passing the end of an initial thread-loop through each of the subsequent thread-loops of a cycle in the same direction.

3. In a machine for making knotted thread-fastenings, in combination, a reciprocating thread-carrier adapted to pass thread-loops through the work, actuating means for imparting a succession of reciprocations to said thread-carrier in each knot-forming cycle, a thread-nipping loop-taker adapted 40 to coöperate with said thread-carrier in handling the thread-loops, means for actuating said loop-taker to nip the thread of the first loop formed by the thread-carrier and to pass it through a subsequent thread-loop, and means coöoperating with said loop-taker in completing the thread-fastening.

4. In a machine for making knotted thread-fastenings, in combination, a reciprocating thread-carrier adapted to pass the 45 thread-loops through the work, actuating

means for imparting a succession of reciprocations to said thread-carrier in each knot-forming cycle, a thread-nipping loop-taker adapted to coöperate with said thread-carrier in handling the thread-loops, actuating 70 means for said loop-taker acting initially to cause the same to nip the thread of the first loop presented thereto by the thread-carrier after the latter has risen above the work and to pass it through a subsequent thread-loop, 75 and means coöoperating with said loop-taker in completing the thread-fastening.

5. In a machine for making knotted thread-fastenings, in combination, a reciprocating thread-carrier adapted to pass the 80 thread-loops through the work, actuating means for imparting a succession of reciprocations to said thread-carrier in each knot-forming cycle, a thread-nipping loop-taker adapted to coöperate with said thread-carrier in handling the thread-loops, a thread-holding device, and means for actuating said 85 thread-nipping and holding members whereby the nipping member is caused to seize and nip the end of the thread of the initial thread-loop of a knot-forming cycle and pass it through a second thread-loop to the holding member, the holding member to retain such thread while the nipping member recedes from the second thread-loop and advances to 90 grasp the thread-end, the nipping member to then pass said thread-end through a third thread-loop to the holding member by which it is retained, and the nipping member to finally recede from the third thread-loop to 95 permit the knot to be set.

6. In a machine for making knotted thread-fastenings, in combination, a reciprocating thread-carrier for passing thread-loops through the work, a coöperating loop-taker having a beak formed with relatively 100 movable jaws, means for actuating said loop-taker whereby one thread-loop is entered by one jaw only of the loop-taker which is operated to nip the same, and a succeeding loop 105 is entered by both jaws of said loop-taker, and means coöoperating with said loop-taker in completing the thread-fastening.

7. In a machine for making knotted thread-fastenings, in combination, a reciprocating thread-carrier for passing thread-loops through the work, a coöperating loop-taker having a beak formed with relatively 110 movable jaws, means for imparting to said loop-taker an operative loop-taking movement for each reciprocation of the thread-carrier, independent means for operating said jaws whereby one only of the latter is caused to enter one thread-loop upon which the other jaw is then closed and both jaws to 115 enter a subsequent thread-loop, and means coöoperating with said loop-taker in completing the thread-fastenings.

8. In a machine for making knotted 120 stitches, the combination with means for 125

- passing the thread around a portion of the material and forming a succession of thread-loops at the same point on one side of the portion so embraced, of means for passing 5 through each of said thread-loops the end of the thread from the opposite side of said embraced portion of the material, and means for drawing up the thread to complete the knotted stitch.
10. A machine for making knotted fastenings comprising a thread-carrier, means for reciprocating the same longitudinally and laterally, knot-tying devices comprising a pair of gripping members, means for simultaneously moving said gripping members laterally in one direction, means for moving said gripping members toward and away from each other in a direction transverse to the first-said motion, means for causing said 15 gripping members alternately to grip and release a portion of the thread, and a cutter arranged to sever the thread on the completion of a cycle of knot-tying operations.
10. A machine for making knotted fastenings for connecting parts, comprising a laterally and longitudinally movable thread-carrier constructed and arranged to carry a thread around portions of the work, and knot-tying devices comprising two laterally 20 movable gripping members, means for actuating one of said members to grip a loose end of thread extending from the carrier and carry it around said carrier and through a loop formed in the thread by said carrier, means for moving the second of said gripping members toward and away from said first gripping member, and means to cause 25 said second gripping member to engage the end of thread held by the first gripping member.
11. A machine for making knotted fastenings for connecting parts comprising a thread-carrier, means for reciprocating said carrier longitudinally and laterally, and knot-tying 30 devices comprising a pair of gripping members, means for simultaneously moving said gripping members laterally in one direction, means for moving said gripping members toward and away from each other in a direction transverse to their first said motion, and means for causing said gripping members alternately to grip and release a portion of the thread, whereby said members are caused to carry an end of thread partially around the 35 carrier and draw the same through a loop in the thread formed by the retraction of the carrier.
12. In a machine of the character specified, knot-tying instrumentalities comprising gripping members each having a nipper pivoted thereto, a cam having engaging surfaces arranged to act on said members to move them toward and away from each other, a second cam connected to said members to move 40 them transversely to their first motion, a reciprocating member having means for engaging the fingers of said gripping members and arranged to separate the fingers of one of said members in its movement in one direction and to separate the fingers of the other of 45 said members in its movement in the opposite direction, and means for actuating said reciprocating member.
13. In a machine of the character specified, a holder journaled in the frame of the machine, a pair of knot-tying gripping members journaled in said holder, a nipper pivotally mounted on each of said gripping members and arranged to coact with said members to grip a thread, arms journaled in fixed bearings in alinement with the journal of the gripping members and each engaged with one of the gripping members, a cam having means for engaging said arms and moving them, and thereby the gripping members to 50 grip and release a portion of the thread, and a second cam, connections between said cam and the holder whereby the latter is oscillated about its journal, and means for operating the nippers alternately.
14. In a machine of the character specified, a holder journaled in a fixed bearing in the frame of the machine, gripping members journaled in a bearing in said holder perpendicular to the bearing for the holder, nippers 55 carried by said gripping members and pivotally connected thereto, cam surfaces having connections with said gripping members and arranged to move the latter toward and away from each other, a cam connected to the holder and arranged to oscillate said holder in its bearing, a reciprocating rod having projections located and arranged to engage the nipper carried by one of the gripping members in its forward movement and to engage the nipper carried by the other of 60 said gripping members on its backward reciprocation, and means for reciprocating said rod.
15. A machine of the character stated comprising a needle-bar, a needle carried thereby, means adapted to reciprocate said needle-bar at a uniform speed, a cam connected to said needle-bar to shift the same laterally and arranged to hold the bar in one position 65 while the latter makes one reciprocation, then to shift the bar and hold it in the second position while it makes two subsequent reciprocations, the aforesaid motions constituting the cycle of operations in forming a complete knotted fastening, and knot-tying devices comprising a gripping member, operating means therefor arranged to hold said member in the path of the needle during the first reciprocation thereof and cause said 70 member to grip the end of a thread carried by the needle, then to move said member to one side of the path of the needle and partially around the needle during the second reciprocation thereof, a second gripping 75

member, and operating mechanism therefor arranged to advance the latter to the first gripping member while the needle is commencing the return stroke of its second reciprocation and cause said second member to grip the thread-end carried by the first member and draw the thread through a loop formed in the thread while the needle is being retracted, and then to deliver the thread-end to the first gripping member, said operating mechanism being further constructed and arranged to cause the said gripping members to repeat the above-mentioned cycle of operations during the third reciprocation of the needle.

16. A machine for making knotted connections, comprising a work - support, a thread-carrier and a plurality of coöperating gripping members all adapted for relative operative movement in parallel planes and positioning movements transversely thereof, and operating mechanism for passing the carrier and a thread through separated points in the work, and for causing the gripping members to carry one portion of the thread through a loop in the thread passed through the work by the carrier.

17. In a machine of the character specified having a needle and knot-tying devices comprising a thread-nipping loop-taker and arranged to perform a cycle of knot-tying operations, a take-up normally acting to set the knots, and means auxiliary thereto for providing at the end of each knot-tying cycle a measured supply of thread for beginning the next knot-forming operation, comprising relatively stationary thread-guides, the position of one of which is determined by the character of the work, a relatively movable thread-guide, and means for shifting the movable guide in respect of the relatively stationary guides to draw thread from the thread supply.

18. A machine of the character specified comprising a thread-carrier, means for longitudinally reciprocating said carrier, means for shifting the carrier laterally, said means being arranged to cause the carrier to make one reciprocation, then to shift the carrier and cause the carrier to make a plurality of reciprocations in its second position, thread-engaging means coöperating with said thread-carrier in forming a fastening, thread-guides, a thread-clamp, and means for operating said clamp to grip the thread during the first portion of the movement of the carrier in the third reciprocation of the cycle.

19. In a machine for making knotted stitches, the combination with a longitudinally reciprocating thread-carrier and a work-support and means for producing relative lateral movements of the one with reference to the other whereby the thread-carrier is caused in the cycle of operation of the machine to make a single reciprocation in

one position, and two successive reciprocations in another position in respect of the work - support, complementary knot-tying means coöperating with said thread-carrier in forming knotted stitches and a thread-cutting device, of a normally - open thread clamp, and means for actuating the same to grip the thread during the first portion of the carrier's movement in its third reciprocation and again during the operation of said thread-cutting device in cutting the thread.

20. A machine of the character specified having instrumentalities adapted to cause a cycle of knot-tying operations, means for cutting the thread on the completion of the cycle comprising a knife, a guide in which said knife is movably mounted adjacent the work, and actuating mechanism therefor comprising a pivoted lever operatively connected thereto and provided with a cam surface, a lever pivoted to the machine-frame in engagement with said cam surface, and mechanism connected to oscillate said second lever.

21. In a machine for making detached knotted thread fastenings, a carrier constructed and arranged to carry a thread-end through the work and to carry a loop of thread around a portion thereof, knot-tying gripping members arranged to grasp the thread-end and perform a series of knot-forming operations, a cutter for severing the thread at the conclusion of one series of knot-tying operations, a thread-supplying device for furnishing at the conclusion of one series of operations a sufficient supply of thread to begin the next knot-tying operation, and means for operating said cutter and thread-supplying device, arranged to operate first the supplying device and immediately thereafter the cutter.

22. In a machine for making detached knotted thread fastenings, a carrier constructed and arranged to carry a thread-end through the work and to carry a loop of thread around a portion thereof, knot-tying gripping members arranged to grasp the thread-end and perform a series of knot-forming operations, a cutter for severing the thread at the conclusion of one series of knot-tying operations, a thread-supplying device for furnishing at the conclusion of one series of operations a sufficient supply of thread to begin the next knot-tying operation, means for operating said thread-supplying device to draw off a supply of thread, and connections between said supplying device and cutter whereby the latter is actuated to sever the thread by the supplying device at the conclusion of the operative movement of said device.

23. A machine of the character specified comprising instrumentalities adapted to cause a cycle of knot-tying operations, a cutter for severing the thread, a lever having

a thread guide, connections between the cutter and lever whereby the former is operated by the latter, and means for moving the lever at the conclusion of each cycle to draw thread from the supply and sever the thread.

5 24. A machine of the character specified comprising instrumentalities adapted to cause a cycle of knot-tying operations, a cutter for severing the thread, a lever having a
10 thread guide and a projection, an arm connected with the cutter having a cam surface

engaged by said projection, whereby the cutter is operated by the lever, and means for moving the lever at the conclusion of each cycle to draw thread from the supply 15 and sever the thread.

In testimony whereof I have affixed my signature, in presence of two witnesses.

CHARLES M. MORTON.
